US0D1078052S

(12) **United States Design Patent** (10) **Patent No.:** **US D1,078,052 S**
(45) **Date of Patent:** **** Jun. 3, 2025**

(54) **MEDICAL DEVICE**

(71) Applicant: **Owen Mumford Limited**, Woodstock (GB)

(72) Inventors: **Chris Thursfield**, Woodstock (GB); **Laurance Turner**, Woodstock (GB); **Rob Jordan**, Woodstock (GB); **Rob Hall**, Woodstock (GB)

(73) Assignee: **OWEN MUMFORD LIMITED**, Oxfordshire (GB)

(**) Term: **15 Years**

(21) Appl. No.: **29/837,118**

(22) Filed: **May 2, 2022**

(30) **Foreign Application Priority Data**

Nov. 3, 2021 (GB) 6173749
(51) **LOC (15) Cl.** **24-02**
(52) **U.S. Cl.** **D24/169**
(58) **Field of Classification Search**
USPC D24/113, 130, 131, 169; D13/162, 184
CPC A61M 5/14244; A61M 5/14248; A61M 2005/14252; A61M 2005/1426

See application file for complete search history.

(57) **CLAIM**

The ornamental design for a medical device, as shown and described.

DESCRIPTION

FIG. 1 is a front elevational view of a medical device showing our new design;

FIG. 2 is a right side elevational view of the medical device of FIG. 1;

FIG. 3 is a left side elevational view of the medical device of FIG. 1; and,

FIG. 4 is an isometric view of a top, front, and right side of the medical device of FIG. 1.

1 Claim, 4 Drawing Sheets
